UNITED STATES PATENT OFFICE.

GEORGE BENDER, OF EVANSVILLE, INDIANA.

SUBMARINE LIFE-BOAT.

1,260,955.

Specification of Letters Patent. Patented Mar. 26, 1918.

Application filed February 2, 1917. Serial No. 146,169.

To all whom it may concern:

Be it known that I, GEORGE BENDER, a citizen of the United States, residing at Evansville, in the county of Vanderburgh and State of Indiana, have invented new and useful Improvements in Submarine Life-Boats, of which the following is a specification.

Broadly stated, the invention comprehends the provision of means for transporting merchandise, and the crew of a disabled submerged boat, to the surface of the water, the invention being particularly intended for use in conjunction with submarines.

More specifically stated the invention makes use of a cask adapted to be securely yet removably associated with the shell of the boat, the cask being adapted to receive merchandise and to be entered by the crew of the boat should the latter become disabled when submerged, and capable of rising to the surface of the water when separated from the boat.

In carrying out the invention I provide means operable from the inside of the cask for securely and detachably holding the latter associated with the boat, together with a fluid-tight connection which surrounds the entrance openings provided in the boat and cask respectively.

Another important characteristic of the invention resides in the provision of a float which is secured to the boat by means of a flexible element, and held in proper position on the boat by the cask, so that when the cask is separated from the boat the float is liberated, or in other words permitted to rise to the surface of the water, thus indicating the particular location of the submerged vessel.

Other important features of the invention will appear as the nature of the same is better understood from the following detail description when taken in connection with the accompanying drawings, the invention residing in the construction, combination and arrangement of parts as claimed.

In the drawings forming part of this specification like numerals of reference indicate similar parts in the several views and wherein:

Figure 1 is a vertical sectional view through the cask and float, these parts being arranged in position relative to the boat.

Fig. 2 is a detail sectional end elevation.

Fig. 3 is a top plan view partly in section,

Fig. 4 is a fragmentary side elevation.

Referring to the drawings in detail A indicates the upper shell of the boat upon which the cask indicated generally at B is supported. The cask B may be constructed from any suitable material, size, and cross sectional configuration, and is primarily provided to receive the merchandise from the boat A, and also the crew should the boat become disabled when submerged. The invention is applicable for use with different type boats or vessels, but is primarily intended for use in connection with submarines. The upper shell of the boat A is provided with a man hole 10 disposed in alignment with a similar hole or opening 11 in the floor of the cask B, so that communication can be readily established between the boat and cask respectively as the occasion may require, the openings 10 and 11 being normally closed by means of screw ring-like covers 12.

Secured upon the upper shell A of the boat and surrounding the man hole 10 therein, is an annulus 13 substantially of Z-shaped formation in cross section, whereby one of the horizontal flange portions indicated at 14 provides for the attaching of the annulus to the boat, while the other horizontal flange portion 15 is spaced above the shell A to cooperate with suitable fastening means carried by the cask for holding the latter fixed upon the boat. It is of course to be understood that what is herein shown and described constitutes one and the preferred embodiment of the invention, and is not to be considered restrictive, as various changes may be resorted to when desired, and any suitable means employed for securing the cask to the boat other than what is shown, without departing from the spirit of the invention. However a plurality of sleeve-like members 16 are secured to the bottom or floor of the cask, while rotatably mounted in each of said sleeves is a substantially L-shaped rod 17, the relatively short branch 18 of which projects beneath the floor of the cask and disposed with relation to the flanged portion 15 of the annulus 13, to engage beneath the latter when the rod is rotated in one direction, to assist in holding the cask in position upon the boat. It is of course manifest that when the rods 17 are rotated in an opposite direction the relatively short branches 18 of the respective rods are moved from beneath the flanged

portion 15 of the annulus, with a view of detaching the cask from the boat. A lever 19 is preferably employed for rotating the rods 17, and said levers are arranged within 5 the cask being associated with the upper extremity of the rod. A gasket or other suitable packing 20 is interposed between the flanged portion 15 of the annulus, and the bottom or floor of the cask, whereby a fluid- 10 tight joint is provided between these respective parts thus eliminating any possibility of water gaining access in the space between the boat and cask about the man holes 10 and 11 respectively.

15 Substantially Z-shaped brackets 21 are secured to the shell A at opposite sides of the cask B, and are provided to coöperate with substantially L-shaped latch elements 22 arranged exteriorly of and carried by the cask 20 B, to assist in holding the cask positioned upon the boat. Each latch element 22 is fixed upon a shaft 23 which passes through a stuffing box 24 in one side of the cask, the shaft being mounted for rotation. Arranged 25 within the cask and carried by the adjacent extremity of the shaft 23 is an operating lever 25 through the instrumentality of which the shaft is rotated. With the lever 25 normally in true vertical position the 30 branch 26 of the latch element 22 is engaged beneath the horizontal flange 27 of the bracket 21 whereby the cask is effectively locked on the boat A, and assists the locking means hereinabove described in accomplishing 35 this purpose. However when the lever 25 is swung in either direction, the shaft 23 is rotated to effect a release of the latch element 22 from the bracket 21, to permit the cask to be separated from the boat as the occasion may require.

The cask B is equipped with a motor of any suitable character indicated generally at 28, but by preference the motor is of the gasolene type. Arranged in one corner beneath the top of the cask B is a compartment 45 for the gasolene tank indicated at 29. The motor embodies a propeller shaft 30 which projects through the cask adjacent one end, the shaft being provided with a propeller of any suitable type indicated at 31.

The top of the cask B is provided with door openings, which are normally covered or closed by doors 32, the latter being preferably hinged to one side of the cask, and effectively held in closed position by the clamps 33 which are of a construction similar to the construction of the clamps hereinbefore described in connection with the annulus 13.

In practice, should the boat become disabled when submerged, the covers 12 are removed from the man holes 10 and 11 respectively, to establish communication be- 65 tween the boat A and the cask B. When the

merchandise has been transported from the boat into the cask, the crew enters the latter, and separates the cask from the boat by operating the levers 19 and 25 respectively in the manner above stated. The cask being an air tight vessel will rise to the surface of the water, when separated from the boat. The motor of course is then put in operation to propel the cask to the desired destination. Arranged exteriorly of the cask and fixed upon the shaft 23 for adjustment therewith, is a substantially semicircular arm 34, the opposite extremities of which are pointed and normally project a slight distance below the floor of the cask as clearly shown in Fig. 4. When the lever 25 is adjusted in either one or the other direction to effectively release the latch elements 22, one end of the arm 34 is brought into engagement with the top of the boat, and upon further adjustment of the lever 25 the arm 34 serves to push the cask away from the boat thereby assisting the cask to begin its flight to the surface of the water.

Arranged upon the boat A in juxtaposition to the cask B is a float 35 which has its bottom spaced a considerable distance from the top of the boat to provide a compartment for the reception of a flexible element 36, the latter having one end connected to the bottom of the float and its opposite end connected to the top of the boat, while the element normally is coiled within the compartment above referred to and clearly illustrated in Fig. 1. A clip 37 is secured to the top of the boat, and engages a similar clip 38 carried by the float to assist in holding the latter positioned upon the boat. As shown the cask B is provided with an inclined portion 38 through which the propeller shaft 30 projects, the inclined portion providing sufficient space for the reception of the propeller plate 31. Carried by the float is an angle plate 39, the projecting branch 40 of which is normally disposed beneath the inclined portion 38 of the cask, and coöperates therewith to hold the float in position upon the boat. However when the cask B is separated from the boat, and starts on its journey to the surface of the water, the float is automatically released from the boat and also rises to the surface of the water, but still held connected to the boat through the medium of the flexible element. The float thus serves as an indicator to 115 designate the particular location of the submerged vessel in the body of water.

While I have shown and described what I consider the preferred embodiment of the invention I desire to have it understood that changes in the construction and arrangement may be resorted to when desired as fall within the scope of what is claimed.

What is claimed is:—

1. The combination with a submersible 130

- boat, of a cask detachably supported thereon and communicating therewith, means for controlling said communication, flanges rising from said boat, retaining elements carried by the cask for swinging movement, and engaging said flanges for holding the cask in position upon the boat, levers controlling the movement of said retaining elements, said levers being disposed within the cask, means operable from said levers for moving the cask initially away from the boat subsequent to the release of the retaining elements. 5
2. The combination with a submersible boat, of a cask detachably supported thereon and communicating therewith, means for controlling said communication, flanges rising from said boat, shafts journaled in the sides of said cask, retaining elements carried by the shafts and disposed exteriorly of the cask and coöperating with said flanges for holding the cask positioned upon the boat, levers disposed within the cask for rotating said shaft to effect a release of the cask, and 10
3. The combination with a submersible boat, of a cask detachably supported thereon and communicating therewith, means for controlling said communication, manually operable means for effecting a release of the cask from the boat, said cask having an inclined bottom portion adjacent one end thereof, a flange rising from the boat, a casing mounted upon the boat and constituting a float, lugs projecting from the casing, one 15 of said lugs engaging beneath said flange and the other lug engaging the inclined bottom of the cask, whereby said float will be automatically separated from the boat subsequent to the separation of the cask therefrom. 20

In testimony whereof I affix my signature.
GEORGE BENDER.
